FERDINAND SOUCZEK, OF NEAR CESKA LIPA, BOHEMIA, ASSIGNOR TO VEREENIGDE
TEXTIEL-MAATSCHAPPIJEN MAUTNER, OF ROTTERDAM, NETHERLANDS.

SHUTTLE-CHECKING MECHANISM FOR WEAVING LOOMS.

Application filed July 14, 1925, Serial No. 43,571, and in Germany July 8, 1924.

In ordinary weaving looms, the stopping of the shuttle entering the shuttle box at a great speed is effected almost exclusively by braking it by means of a spring controlled tongue or ledge projecting into the shuttle box. This braking takes place with a perfectly uniform retardation, as the spring pressure remains constant as soon as the shuttle has displaced the shuttle box tongue.

10 The working diagram in this case is practically a rectangle represented in Figure 4 of the accompanying drawing by the surface O. A. E. If however the shuttle is received by springs for the purpose of recovering the 15 momentum which it still possesses on coming into the shuttle box, namely in such a manner that the springs act on the shuttle directly or in a constant ratio indirectly, the springs are brought uniformly from their 20 tension-less state to the state of their maximum tension at the end; in this case the working diagram will be a triangle corresponding to the surface O. B. E. in Figure 4. It is clear that with equal area of the 25 working diagram, that is to say with equal brake work, the mechanical stresses on the brake device in this case will be much greater, owing to the great end-tension, than in the first case. Finally, if the springs are 30 so arranged that they act on levers and replace the elasticity of the arc of a cross-bow, the braking force will be still greater for the same work, as shown by the line O—C in Figure 4.

35 By the present invention, the counter-force acting by means of springs on the shuttle can be given any desired course; moreover this invention ensures also a very great reduction of the mass accelerations, owing to 40 which not only the braking and picking or shooting is effected in a manner perfectly corresponding to the law of motion, but also a very high efficiency in respect of recovery of the momentum of the shuttle is obtained.

45 A constructional form of this invention is shown in the accompanying drawing in which Figure 1 is a front elevation of the arrangement of the right hand shuttle box before the arrival of the shuttle and Figure 2 50 after its arrival. Figure 3 is intended to show the forces, and Figure 4 the working during the braking or picking of the shuttle.

To the rear wall of the shuttle box guide 1 is secured a carrier arm 2 which supports the

bearings 3 for two rotatable curved discs 4. 55 Round the two curved discs is placed a flat belt or strap 5 secured thereto. At some distance from their centre of rotation the curved discs engage tension springs 6, the other ends of which are attached to a support 7, 60 Figure 2, secured to the rear wall 1 of the shuttle box.

These springs are always under tension and therefore hold the two curved discs in the position shown in Figure 1, the strap or 65 belt 5 being held taut. This strap is of such a length that the rectilinear ends 8 of the curved discs 4 forms a straight line with the strap 5. Further the strap is loosely passed through the leather eye 9 of the cork picker 70 10. The picker 10 has the same cross-section as the shuttle guide or race, so that the shuttle race at the same time forms the picker guide. At the front and rear ends of the central part of the cork picker are secured 75 protecting means such as leather end pieces.

When on arriving the shuttle strikes the picker or driver, it brings the picker into the position shown in Figure 2, the belt pulled with it being lifted off the convex surfaces 80 of the two curved discs which latter are at the same time turned through a certain angle, owing to which the tension of the springs is still further increased. The brake block 11 described in U. S. Patent No. 1,568,036, 85 is in this case operated so that its swinging support 12 is brought by the spring 13 engaging with it, into the brake batten at the moment when the segment 14 secured to the lower disc 4 leaves the roller 15 of the swing- 90 ing support 12.

Figure 3 shows the action of the forces, the section l or l_0 indicating the leverage relatively to the belt or strap tension Q_u at the time. This force moment is balanced by 95 that of the spring force p with its leverage r , so that $p \times r = Q_u \times l$. The force P which acts on the shuttle or on the driver, follows from the belt tension Q_u at the time, and is at any time equal to $2Q_u \cos \beta$, or 100

$$\left(\text{since } Q_u = \frac{pr}{l} \right) = \frac{2pr \cos \beta}{l}$$

Here the angle β is the angle which the belt or strap makes with the shuttle race. The 105 object of the curved stretchers is therefore to bring the force P which in Figure 1 is zero (as the angle β is 90 degrees) quickly to

a maximum which, during further penetration of the shuttle or rotation of the stretchers, remains without modification, which is effected by the leverage l being modified by the curvature of the stretchers, in accordance with the progressing change of the angle β .

It is obvious that the change in itself inconsiderable of the spring force p and of the leverage r , must be taken into account in calculating the shape of the curve.

The line O—D in Figure 4 shows the course of the counterforce B which is obtained with the stretchers shown in Figures 15 1 and 2.

Another essential advantage of this arrangement is that the springs 6 are exposed in working only to slight changes of tension owing to which their life is lengthened.

20 The rectilinear end portion 8 of the stretchers 4 has for its object to keep them in symmetrical initial position, so that the strap starts a uniform distribution of the forces at the arrival of the shuttle.

25 It is to be understood that the invention is not limited to the foregoing embodiment which is given only by way of example, as the details of construction may be modified or changed without departing from the spirit 30 or scope of the invention defined by the following claims.

What I claim and desire to secure by Letters Patent of the United States is:—

1. In shuttle mechanism for weaving 35 looms, a picker arranged in the path of the shuttle, two pivotally mounted spring controlled curved stretchers on either side of the path of the shuttle, and a flexible belt stretched across the path of the shuttle and fixed on either end to one of the stretchers, the latter having a flat portion next to the path of the shuttle and a curved portion adjoining the flat portion, the curved portion being so shaped that on the stretchers being 40 turned by the belt under the impact of the shuttle, the leverage relatively to the belt tension quickly increases to a predetermined 45

maximum and during the further progress of the shuttle remains stationary.

2. In weaving looms, shuttle mechanism 50 comprising a shuttle, a race for said shuttle, a picker on said race, two curved stretchers pivotally mounted on either side of the race, a flexible belt stretched across the path of the shuttle and fixed on either end to one of the 55 stretchers, and springs connected to said stretchers for holding the belt normally taut, said stretchers having a flat portion next to the path of the shuttle and a curved portion adjoining the flat portion, the curved portion being so shaped that on the stretchers being turned by the belt under the impact of the shuttle, the leverage relatively to the belt tension quickly increases to a predetermined maximum and during the further 60 progress of the shuttle remains stationary.

3. In weaving looms, shuttle mechanism comprising a shuttle, a race for said shuttle, a movable cork picker having a cross-section corresponding with the cross-section 70 of said shuttle race, leather end pieces for said picker, a belt support for said picker and two rotatable spring-controlled curved stretchers to which the ends of the belt support are attached, the arrangement being 75 such that the shuttle upon striking the picker causes the belt support to rotate said stretchers against the action of their springs.

4. In weaving looms, shuttle mechanism 80 comprising a shuttle, a race for said shuttle, a movable cork picker having a cross-section corresponding with the cross-section of said shuttle race, leather end pieces for said picker, a belt support for said picker and two rotatable spring-controlled curved 85 stretchers to which the ends of the belt-support are attached, said curved stretchers having a flat portion adapted to contact with said belt support when said picker is in its 90 normal position of rest.

In testimony whereof he affixes his signature.

FERDINAND SOUCZEK.
